ROTARY VALVE CONTROLLED INTERNAL-COMBUSTION ENGINE

Roland Claude Cross, Bath, England

Application May 6, 1943, Serial No. 485,925
In Great Britain September 18, 1941

8 Claims. (Cl. 123—80)

This invention relates to internal combustion engines operating under the control of a cylindrical or other rotary valve, and of the kind wherein the explosion and compression pressures in the engine cylinder are partly utilised for pressing the valve housing on to the rotary valve to provide a gas and fluid tight seal therebetween. This kind of internal combustion engine generally includes a valve housing divided longitudinally into two parts, and a cylinder slidably mounted in the crank case and carrying solidly as part of its head one part of the valve housing, whereby when pressures are generated in the cylinder the latter with its housing part is caused to press outwardly with respect to the crank case against the outer housing part or cap and against the enclosed rotary valve. Examples of such a construction are to be seen in various Cross British patent specifications for example Nos. 448,368, 448,383, 448,384, 451,917 (with its corresponding U. S. No. 2,169,631, dated Aug. 15, 1939) and British Patent 467,620. In others, the cylinder itself is not actually movable but as an equivalent the inner housing part is formed as part of a body, slidable in the cylinder and constituting virtually a yieldable cylinder head responsive to the aforesaid pressures, and examples of such a variation are to be found in the Cross British Patents Nos. 474,521, 481,933 and 504,709.

The present invention is applicable to these various constructions which introduce divided valve housings, and also to other designs wherein a movable cylinder is adapted to press the housing on to the valve.

For convenience of description the movable parts may be termed "floating" and in this specification such a term denotes that the member so described is yieldable in relation to other parts, such as in relation to the fixed crank casing and other firm parts of the engine, so as to yield and be capable of transmitting varying pressures applied thereto to another member contacting therewith, whether the said floating member is perceptibly displaced or not. The term "stationary" where applied to a part denotes that that part is non-floating in the above sense but stands immovable together with firm parts of the engine, and offers a solid resistance to any pressures applied thereto.

Hitherto in engines of the foregoing kind, the cylinder or other floating element to which the pressure generated in the cylinder is directly applied moves in a straight line, e. g., axially in the case of a cylinder. Although this simple move-

ment can be utilised quite easily in the case of an overhead rotary valve, it may involve complications to adapt the principle underlying this kind of engine to a layout where the rotary valve is disposed towards one side of the cylinder. It is true that an offset rotary valve is shown in the aforesaid prior British Patent No. 467,620, but in this case the arrangement is still in effect an overhead valve as the location is not sufficiently off the cylinder center to enable it to be placed lower and alongside the cylinder for cutting down overhead room which is an important advantage of a "side" valve engine. The present invention is particularly designed for applying the principles in the aforesaid kind of engine to a side valve engine of the rotary valve type. The invention however is not confined to such a disposition of valve as the advantages flowing from pivoting the cylinder (explained later) can be usefully adapted to overhead valve engines.

According to the said invention, the cylinder or equivalent floating element to which the pressure generated in the cylinder is directly applied is carried on a pivotal axis offset from the axis of the cylinder so that it will tend to rock about such a pivotal mounting when a pressure is set up in the cylinder, and this rocking movement, as distinct from the known rectilinear movement, is utilised for applying sealing pressure between valve and housing.

An engine incorporating the present invention may be combined with a system for controlling the amount of pressure ultimately exerted by the housing parts on the valve wherein the outer housing part is also a floating element suitably coupled to the lower housing or other floating part (according to the aforesaid prior British Patent No. 451,917 and its U. S. counterpart No. 2,169,631, and British Patents Nos. 467,620, 474,521, 481,933 and 504,709, and 479,539). An important advantage of the present invention is that it is inherent in the design that the pressure ultimately applied to the valve is controlled, such control arising out of the possibility of locating the pivot about which the aforesaid rocking movement takes place in any requisite position. Thus, even with a stationary outer housing part, the engine is nevertheless capable of construction with a measure of control.

In order that the said invention may be clearly understood reference is directed to the following description, aided by the accompanying drawings, wherein—

Figure 1 is a diagram showing the invention

applied to a case where the outer part of the divided valve housing is stationary;

Figure 2 is a diagram showing the invention applied to a case where the outer part of the divided valve housing is floating;

Figure 3 is a diagram similar to Figure 2 but with a different arrangement of floating outer part of the housing;

Figure 4 is another diagram similar to Figure 2 but with the floating housing part under the control of a tie-rod;

Figure 5 is a diagram showing a form where the housing parts are pressed together in a vertical direction, the outer part being stationary;

Figure 6 is a diagram showing the invention applied to a non-divided housing and wherein the valve is of the conical plug type; and

Fig. 7 is a detail sectional view of a construction according to the Fig. 1 diagram.

Fig. 8 is a detail sectional view through a portion of a side valve engine of the horizontal, opposed cylinder type embodying valve sealing means in accordance with the invention; and

Fig. 9 is a diagrammatic view of another embodiment of the invention.

Referring generally to Figures 1-5 and 7 and 8, the cylinder 1 is movably mounted in the crank case 2 and supported by the pivot A which is the important feature of the invention. The rotary valve 3 is carried in the housing consisting of two divided parts, an inner part 4 rigid with the cylinder and an outer part 5. Pressures generated in the cylinder will react against the cylinder head and tend to rock the cylinder about the pivot A in the direction of the arrow B. This presses the inner housing part 4 on to the valve 3 in the direction of arrow C (Figures 1-5) to accomplish the desired sealing. Obviously, the amount of pressure in the direction of the component C can be controlled when designing the engine by suitably locating the pivot A which may be nearer to or farther from the axis of the cylinder (for example on a trunnion axis as in Figure 5), and nearer to or farther from the axis of the rotary valve 3.

Dealing with the case illustrated in Figure 1, the controlled pressure resulting at C is applied unmodified to the valve 3 inasmuch as the outer valve housing part 5 is stationary mounted rigidly on or in respect to the crank case and offers an uncontrolled resistance to the force C. No particular method of rigidly mounting the cap 5 as a stationary member is indicated in this figure, but the arrow Z is intended to denote a solid resistance and rigidity.

In Figure 2 the outer valve housing part 5 is a floating member hinged to the other part 4 at E, and supported on the fixed pillar or strut D. As in the previous case, part of the explosion and compression pressures tend to force the cylinder out of the crank case. As mentioned, the cylinder is mounted slidably in the crank case but hinged thereto at A with the result that the pressure resolves itself into a tendency to cant the cylinder in the direction of arrow B. This gives a component in the direction of arrow C and thus the left-hand half of the rotary valve housing, which is solid with the cylinder, is pressed against the rotary valve. The pressure in the direction of the arrows B, C however is brought up against a solid resistance at the top of the supporting pillar D. As the valve housing is divided into two parts hinged at E the forces tend to press the point E downwards in the direction of arrow F. The resistance or reactions set up

are taken by the yieldable right-hand half of the valve housing which may be regarded in two senses as a bell crank lever. Firstly, it is a bell crank lever pivoted at E with the two arms axially depicted by GE and EH. As a result of the forces just described this bell crank tends to move in the direction of the arrows at G and H; the right-hand half of the housing also operates as a bell crank fulcrumed at D having the arms axially depicted at JD and KD. Movement of the pivot E in the direction of the arrow F, or the tendency to such a movement, will tend to rock the bell crank JD, DK about the fulcrum D setting up pressures in the direction of arrows J and K. The net result of such reactions and resistance is the transfer of some of the pressure originating at C to the valve cap in the direction of arrow L. It will be seen therefore that the part of the explosion and compression pressures operating outwardly against the head of the cylinder is shared by the two halves of the valve housing each operating inwardly towards the centre of the rotary valve along the opposed general directions C and L. The respective fractions of the total available pressure so utilised are controlled by the design and pivotal positions of the various parts, viz: firstly, the location of the pivot A outwardly from the crank casing and radially from the axis of the cylinder as in the previous example, secondly, the position of the pivot E from both the axes of the cylinder and the rotary valve, and thirdly, the position of the fulcrum point D particularly in relation to its spacing from both pivots A and E.

Figure 3 is merely another example operating similarly to Figure 2, the difference being that the outer valve housing part 5 is slidable in the inner part 4 somewhat like the construction of the aforesaid British Patent No. 504,709, and the bell-crank action of the Figure 2 form is taken over by the actual bell-crank 6.

In Figure 4 the direction of the canting action of the cylinder is varied by positioning the pivot A on the other side of the cylinder axis. The outward force of the cylinder pressures, in this case, causes a tendency for the cylinder to move as at B. The outer housing part 5 is a floating member hinged to the part 4 at M; it is held in position by connecting the lever N to the crank case 2 by the tie-rod 7. By this arrangement, the force B brings about a tendency to rise at the hinge M, and whilst movement is restrained by the tie-rod 7 through the lever N, the result is a pincer pressure by the two housing parts 4 and 5 as indicated by the arrows X and Y, and the consequent inward component forces C and L as in the other cases.

Another example of the stationary outer valve housing part 5 according to the diagram Figure 1 is depicted in Figure 5. This part 5 is in the sliding block form of Figure 3 and the prior British Patent No. 504,709, but the example is introduced to show a case where the valve housing parts 4 and 5 are pressed together in a vertical direction. The outer housing part 5 rests solidly on the crank case 2 which in this case affords the solid resistance indicated by the arrow Z in Figure 1.

Like letters and numerals of reference indicate the same or corresponding parts and pressures in the several figures.

In Figure 6 the valve housing, indicated this time as a whole by the numeral 13, is undivided and carries solidly by the cylinder 1, the latter being mounted as in the other cases to rock about

the pivot A in the direction of arrow B. In the housing 13 is a conical plug type of rotary valve 14 supported rigidly by the hollow shaft 15 which offers a firm resistance against the pressure applied to the valve by its housing and originating from the force B. It will be apparent that the pressures set up in the cylinder will bring about a sealing pressure between the housing 13 and the valve, this pressure being controllable as in the other cases by suitably positioning the pivot A.

One of the examples, viz: that outlined in the Figure 1 diagram, will be described in greater detail with the assistance of Figure 7.

Referring to Figure 7, the cylinder is pivoted at A to the crank case 2. The rotary valve 3 is mounted in a housing consisting of the two main parts 4 and 5. The inner part 4 is carried by the cylinder 1 and presses on to the valve as the cylinder is pressed outwards by pressures on the surface 8, all as previously explained. A spring 9 keeps the parts tight and maintains a normal pressure of the housing parts on the valve.

The outer housing part 5 is part of a block 10 slidably mounted on the other part 4. This outer part 5 is held firm as a stationary member by the bracket 11 mounted on the crank case 2. A leaf spring 12 keeps the housing part 5 up to its work, permitting the use of a fair degree of clearance between the block 10 and its accommodating bore in the part 4, and acts generally as a guide and a positioning and locating element, particularly when the block 10 is cylindrical as shown.

The operation of this example needs no further explanation, particularly in view of the previous general description of all the figures and of Figure 1 in particular.

The embodiment in Figure 8 is within the type diagrammatically shown in Figure 1, i. e., the cylinder 1 is hinged at A and carries the inner housing part 4, and also comprises a stationary outer valve housing part 5 held firmly against the valve 3 by a solid resisting member indicated by the arrow Z in Figure 1, and exemplified by the strut 16 in Figure 8. In a general manner the lay-out of Figure 1 has been turned through 90° to produce in Figure 8 a horizontal cylinder construction with the valve offset from the cylinder axis to a side valve disposition. The inner valve housing part 4 is extended as a skirt 17 and brought right down slidably into the crank case sump 20, and the outer housing part 5 is formed as part of a cylindrical body 18 mounted in the skirt 17 and slidable relatively thereto. The housing part 5 is supported by the strut 16 constituting a solid resistance to forces applied to the housing 5 at right-angles to the axis of the cylinder 1.

The sealing pressure between the valve housing parts and the valve is brought about as explained earlier with reference to Figure 1. It will be seen, moreover, that a high degree of cooling of the valve housing particularly the cap-like outer part 5, can be attained by utilising the sump oil as a coolant; the normal level of the oil, in the illustrated example, would be high up the skirt 17 rising inside the cylindrical housing body 18 to about the upper mushroom or ball head of the strut 16. In addition, a feed from the oil circulating system could advantageously be introduced up the duct 19 in the strut 16 for additional cooling.

In a further embodiment illustrated in Figure 9, the cylindrical rotary valve 3 is mounted by its solid stem 20a between "stationary" and rigidly-held bearings 21 carried by a bracket 22

solidly erected from the crank case 2 or other fixed structure, and the housing parts 4 and 5 are fitted around the valve to apply the sealing pressure through the medium of the cylinder 1 pivoted at A. The inner housing part 4 would be pressed against the valve 3 on explosion taking place in the cylinder 2, pressing the lips of the port 23 tightly on contact with the valve, and the outer housing part 5 may be floating or stationary with the strut 16. In all examples according to such a fixed axis valve design the solid reaction or resistance to the pressure originating at the pivoted cylinder would be wholly or mainly taken up by the valve bearings; in the case of Figure 9 the stem 20a (the drive to which has been omitted for simplicity) constitutes a strong rigid beam projecting from the crank case 2.

I claim:

1. An internal combustion engine comprising a cylinder pivoted for rocking movement in response to gas pressure generated therein, a rotary valve for controlling supply of fuel to said cylinder and exhaust of combustion gases therefrom, a plural-part housing for said valve, and means whereby said housing is pressed tightly against said valve in response to rocking movement of said cylinder by gas pressure generated therein.

2. An internal combustion engine comprising a cylinder pivoted for rocking movement in response to gas pressure generated therein, a rotary valve for controlling supply of fuel to said cylinder and exhaust of combustion gases therefrom, a housing for said valve comprising two parts one of which is fixed with respect to the cylinder to swing therewith against the valve and toward the other part, and means restraining the other housing part against moving away from the valve whereby the housing parts are pressed tightly against the valve in response to rocking movement of said cylinder by gas pressure generated therein.

3. An internal combustion engine comprising a cylinder pivoted for rocking movement in response to gas pressure generated therein, a rotary valve for controlling supply of fuel to said cylinder and exhaust of combustion gases therefrom, said valve being disposed at one side of said cylinder and at least partly inwardly of the outer end thereof, and a two-part housing for said valve comprising an inner part movable with said cylinder outwardly against said valve and an outer part restrained against outward movement whereby said housing is pressed tightly against said valve in response to rocking movement of said cylinder by gas pressure generated therein.

4. An internal combustion engine comprising a cylinder, pivoted for rocking movement in response to gas pressure generated therein, a rotary valve for controlling supply of fuel to said cylinder and exhaust of combustion gases therefrom, a two-part housing for said valve comprising an inner part movable with said cylinder outwardly against the inner side portion of said valve in response to rocking movement of said cylinder by gas pressure generated therein, an outer part engaging the outer side portion of said valve, and means whereby said outer part is moved inwardly against said valve in response to rocking movement of said cylinder by gas pressure generated therein.

5. An internal combustion engine comprising a cylinder pivoted for rocking movement in response to gas pressure generated therein, a ro-

tary valve for controlling supply of fuel to said cylinder and exhaust of combustion gases therefrom, a two-part housing for said valve comprising inner and outer parts engaging the inner and outer side portions of said valve, respectively, and means whereby said inner and outer housing parts are moved outwardly and inwardly, respectively, tightly against said valve in response to rocking movement of said cylinder by gas pressure generated therein.

6. An internal combustion engine comprising a cylinder pivoted for rocking movement in response to gas pressure generated therein, a rotary valve for controlling supply of fuel to said cylinder and exhaust of combustion gases therefrom, a two-part housing for said valve comprising an outer part engaging the outer side portion of said valve and restrained against outward movement, and an inner part engaged with the inner side portion of said valve and movable 20 outwardly thereagainst by said cylinder in response to rocking movement of the latter by gas pressure generated therein.

7. An internal combustion engine comprising a cylinder pivoted for rocking movement in response to gas pressure generated therein, a rotary valve for controlling supply of fuel to said cylinder and exhaust of combustion gases there-

from, a two-part housing for said valve comprising an inner part fixed with respect to said cylinder and engaged with the inner side portion of said valve for outward movement thereagainst 5 in response to rocking of said cylinder by gas pressure generated therein, an outer portion pivoted to said cylinder and engaged with the outer side portion of said valve, and means whereby said outer part is swung inwardly against said valve in response to rocking movement of said cylinder by gas pressure generated therein.

8. An internal combustion engine comprising a horizontally disposed cylinder pivoted for downward swinging movement of the outer end portion thereof in response to gas pressure generated therein, a rotary valve at the lower side of the outer end portion of said cylinder for controlling supply of fuel thereto and exhaust of combustion gases therefrom, a two-part housing for said valve comprising an upper part fixed with respect to said cylinder and a lower part restrained against downward movement whereby said housing parts are pressed tightly against said valve in response to rocking of said cylinder by gas pressure generated therein, said engine including a crank case wherein at least a portion of said lower valve housing part is disposed.

ROLAND CLAUDE CROSS.
